ELIAS H. WILLIAMS, OF GRAND MEADOW, IOWA, AND D. R. W. WILLIAMS,
OF WERNER, WISCONSIN.

Letters Patent No. 69,378, dated October 1, 1867.

IMPROVED EXCAVATING MACHINE.

The Schedule referred to in these Letters Patent and making part of the same.

TO ALL WHOM IT MAY CONCERN:—

Be it known that we, E. H. WILLIAMS, of Grand Meadow, State of Iowa, and D. R. W. WILLIAMS, of Werner, State of Wisconsin, have invented a new and improved Machine for Excavating and Moving Earth, it being especially an improvement of the excavator for which Patent No. 35,005 was issued to E. H. Williams, assignee of E. H. and D. R. W. Williams; and we do hereby declare that the following is a clear, full, and exact description of the same, reference being had to the accompanying drawings, making a part of this specification, in which—

Figure 1 is a perspective view of the left-hand side of our invention.

Figure 2 is a plane view of a detached portion of the right-hand side of the same.

Figure 3 is a perspective view, from the rear of the machine, of a detached portion of the same, showing a part of the driving-wheel and the position of the upper sets of pulleys around which the elevating-belts revolve.

Figure 4 is a perspective view of a detached portion of the bottom of the machine, showing a portion of the driving-wheel and the elevating-belts; also, the bottom of the plough, its frame, and draught-bars, and shafts for pulleys placed in the plough-frame.

Figure 5 is a perspective view of the top or upper side of the plough, showing the mould-board, plough-frame, shafts and pulleys, and the draught-bars.

Figure 6 is a perspective view of the right-hand coulter and the block which stiffens it and serves to attach it to the frame of the machine, and also of its wooden continuation, which, with similar left-hand devices, serve to keep the excavated earth between the belts when the machine is in operation.

Figure 7 is a perspective view of the frame that holds the idle pulleys, through which the requisite tension is given to one of the elevating-belts, which, in the description of the machine, we call the pressure-belt.

Similar letters of reference indicate corresponding parts in the different figures.

The parts of the machine shaded red in the different figures are made of wood, and the parts shaded black are iron, except the mould-board and share of the plough, which are of steel, as are the coulters. The belts are shaded blue.

The invention consists in the construction and arrangement, in an excavator, of the pressure-belt V, when the same is driven by friction caused by the ascending furrow-slice, in the manner and for the purpose herein described; second, the construction and arrangement of the two shafts, S S, with their pulleys, in combination with the pressure-belt V, as herein described; third, the combination of the tightening-pulley L', frame L, and pressure-belt V, in the manner and for the purpose herein set forth.

To enable those skilled in the art to construct the invention, we describe it.

The frame G is rectangular and oblong, consisting of three parallel bars, firmly tied by cross-bars at the ends. The inner bar is placed nearer one of the bars, so as to give room for the box E, and not interfere with the discharge of the load through its bottom, and so that the inner bar may support the left-hand coulter and side board, and the wheel A be placed between the bars. The frame G should be of sufficient length to afford room for the wheel A and the plough with its attachments behind it.

The box E is rectangular, and of size to hold an ordinary load. This box is so placed that the back side is nearly over the axle of the wheels A and B. The bottom of the box consists of two hinged doors, which, when closed, are held in their place by the catches a a, fig. 1. These catches are attached to the doors by a rod, chain, and staple, and these catches may have a cord tied to them to pull them up after a load has been discharged. The catches are held by the edge of the plate b, fig. 1.

F (fig. 1) is a slide, to conduct the earth to the box E, and is so placed as to receive it as it is discharged by the belts V and W. M M are posts firmly attached to the frame G, just forward of where the frame G rests upon the axle of the wheels A and B. These posts support the shafts X' and X, of which the shaft X' (fig. 3) is placed on the back side of the posts M M, and the shaft X on the front side of the same, and the shaft X is placed above the shaft X' sufficiently to allow the furrow-slice to pass between the belts V and W, and these

shafts are placed high enough above the frame G to admit of the box E being made deep enough, and also of the delivery of the earth into the box by means of the slide F.

D is a reach, which may be firmly attached to the box E, or, as is preferable, to the frame G, which may be tilted up in front and down behind till the wheels A' A' turn under the reach, and thus a strong attachment is obtained for the reach. To the axle B' may be attached the tongue, through which the power is applied to the machine.

N N are wood spring-poles, which may be of one or more leaves, according to the size of the furrow-slice to be excavated. These springs N N are attached to the forward part of the frame G by means of small upright posts n n, and extend backward over or by the side of the posts M M of sufficient length to be attached by chains or cords to the frame L.

The rods O O are attached to the rear of the plough-frame R, (see figs. 2, 4, and 5,) and extend upward sufficiently to support by the cross-tie O' the springs N N. (See fig. 1.) These rods preserve the tension of the belt V, when the plough is lifted, by lifting the springs. The frame L (figs. 1 and 7) is attached to the upper portion of the posts M M, and contains the pulleys L', and is used to apply the tension of the springs N N to the belt V. (See fig. 1.) By altering the length of the cords or chains which connect the springs N N to the frame L, the tension of the springs can be changed at will.

The side boards K are fastened to the posts M M and to the top of the steel coulters, (see fig. 6,) and the blocks K' are bolted to the bars of the frame G, so as to support the coulters in their proper position, (see fig. 2,) and these blocks must be strong, and strongly fastened, to endure the strain they may be subjected to should the coulters come in contact with what cannot be easily cut or cannot be cut. The coulters should be so placed as to be distant the width of the belts V and W, with the bevel that makes the edge outward, and the curved edge placed as near the rings g' g' of the wheel A as will permit the wheel to revolve. The lower edge should be bevelled in the same manner, and should have the point next the wheel A a little raised, as compared with the heel, and should be low enough to be just above the surface of the ground. (See fig. 2.) These coulters are firmly attached to the block K', made right and left of steel, and should have their inner surfaces polished and the inner and lower edges sharp. The shapes and positions of these side boards, coulters, and attachments are fully shown in figs. 1, 2, and 6.

Q (fig. 1) is a lever, which, by means of a rock-shaft, arm, and connecting-rod, (see Q, fig. 2,) raises and lowers the plough.

P is fastened to the frame G, and its use is to hold the lever Q in any desired position. (See fig. 1.)

H H is a platform, on which the operator stands, who may also manage the team.

The wheel A (figs. 1, 2, and 3) is made with arms, which are slotted to receive the rings g g g, and slotted so that the ends of the arms may slightly project beyond the rings g g g to prevent the belt W from slipping. The rings g g g are made of equal size, of thin, narrow strips, are bent edgewise, composed of two pieces, so they can be placed in the slotted ends of the arms, and are then bolted together so as to form a complete ring. The number of the rings g g g depends upon the breadth of the face of the wheel A, and they should be enough to support the belt W and still leave the spaces between the rings large enough to permit the earth to pass through, if any should get between the belt W and the face of the wheel. The outer rings of the wheel A, g' g', are made whole, and wider than the rings g g g, so as to extend above them sufficiently to keep the belt W upon the face of the wheel A, (see figs. 3 and 4,) and also when any hard substance is run over, to receive the shock and protect the belt. The rings g' g' are bolted firmly to the arms of the wheel A, the bolts passing through them and the rings g g g on each side of the ends of the arms, and also at even distances between the arms, and here the spaces between the rings are preserved by ferrules, through which the bolts pass. In this manner a strong, light wheel is made that will guide, drive, and protect the belt W, and also one that will not admit of earth accumulating upon its face.

The wheel A is keyed upon its axle, which is also the axle of B, a wheel of the same size or radius as A, and, by means of a ratchet, helps drive the elevating apparatus, and offers no obstruction to the turning of the machine when it is turned one way. The frame G rests upon the axle of the wheels A and B, and is attached to the axle by boxes fixed to each of the bars of the frame G. The boxes on each side of the wheel A are made to project beyond the bars of the frame G, toward the wheel A, and are rounded with a rim on the end to receive and retain the clasps u' u', fig. 5, by which the draught-bars W W are attached to the boxes so as to secure the draught of the plough and admit of its being raised and lowered without approaching the wheel A.

The plough (see figs. 2 and 5) is composed of a share and mould-board, corresponding with an arc of a circle described with a radius as much larger than the radius of the wheel A as the thickness of the deepest furrow-slice desired to be excavated, and enough of the arc of such a circle is taken to admit of placing the shafts S S' so high that the belt V (see fig. 4) may not touch the ground.

The mould and share T, so formed as wide as the face of the wheel A, and having their upper surfaces polished, are attached to the forward ends of the bars R R, (see figs. 4 and 5,) which are first turned downward, then inward, then forward and downward, and curved to fit the form of the mould-board. The sides of the plough-frame R R are parallel, and high enough to hold in their proper position the shafts S' S, (see figs. 5 and 2,) and extend back to secure the rods O O, (see figs. 2, 4, and 5,) and are tied at their ends by a cross-bar.

The shaft S', with its pulleys z z, is placed so that there will be room for the belt V to pass around it without touching the ground, and so near to the upper edge of the mould-board that there will be just room enough for the belt V to pass between the pulleys z z and the upper edge of the mould-board T. The shaft S (see fig. 5) is placed parallel to the shaft S', and the pulleys y y are so placed as to be driven by the belt V, and the wheels y' y' are guides of the belt V. Guides are not needed on the shaft S', as the coulters serve this purpose.

The placing the shafts S' S as described leaves a space at the lower fold of the belt V not obstructed with

flanges or pulleys, through which any earth that falls into the fold of the belt may work out. With a single shaft and set of pulleys such earth would be retained and clog the belt V.

The bars U U are firmly bolted to R R, (see figs. 2, 4, and 5,) and attached to the boxes before described by the clasps u' u', so that there will be room for the desired furrow-slice to pass between the plough and the belt W on the wheel A, and so that the share may be set at the proper angle. (See fig. 2.)

The pressure-belt V is made of common rubber belting, of the width of the desired furrow-slice, and is stiffened by cleats of wood, at frequent regular intervals, fastened with elevator-bolts or in any other substantial mode. These slats or cleats are not used as cogs, but only to stiffen the belt and to enable it to revolve on pulleys with faces so narrow that the earth cannot accumulate on them, and such is the construction of the pulleys marked y and x. (See figs. 3 and 5.) The belt V is longer than merely sufficient to connect the shafts S S' and the shaft X, but also of a length to admit the ascent of the furrow-slice between it and the belt W, and the slack of the belt is taken up by the springs N N. The shafts X and X' have belt-guides on them marked x'. (See fig. 3.)

The belt W is of rubber, of the same width as V, and is armored at very short regular intervals by riveting through and through narrow metallic strips placed opposite each other. This belt passes round the wheel A, between the rings g' g', (see fig. 4,) and over the shaft X'. (See fig. 3.) This armor stiffens the belt, keeps the rings g g from cutting it, and saves it from abrasion when it comes in contact with the ground.

Having described the construction of our machine, we now describe its operation: Having attached a single span of horses to the machine, the operator secures the proper tension to belt V, by hitching the springs N N to the frame L, and then steps upon the platform H, starts his team, and then lowers the lever Q and lodges it in one of the notches of P. As the plough enters the ground the furrow rises up, the mould-board is trimmed by the coulters, passes between them, and rises to the belt V, and by it is firmly pressed against the belt W, and as the belt W is carried up by the revolution of A, the friction of the furrow-slice on the belt V sets it in motion, and the ascending furrow-slice, laterally confined by the side boards, is lifted by the belts V and W, the tension of V increasing as the column of earth ascends, till it is thrown out upon the slide F, whence it falls to the box E. This continues till the box is filled, when the lever is raised and the earth between the belts is discharged, when V ceases to move, unless the tension is great, and the machine is driven to the dump and the catches are lowered, the load deposited, and the teams, if desired, all the time in motion. The catches are lifted by the cords attached to them, fastened to plate b, and the machine returns for another load.

The plough is placed so near the wheel A that it never cuts too thick a slice in uneven ground, the wheel lifting the plough as it passes over inequalities, and the plough can always be raised, as in rising it does not approach the wheel A.

This machine, in earth free from roots and stones, works well, is light, durable, easily managed, and requires only ordinary skill to operate it.

Having thus described our invention, what we claim, and desire to secure by Letters Patent, is—

1. The construction and arrangement, in an excavator, of the pressure-belt V, when the same is driven by friction caused by the ascending furrow-slice, in the manner and for the purpose herein described.
2. The construction and arrangement of the two shafts S S, with their pulleys, in combination with the pressure-belt V, as herein described.
3. The combination of the tightening-pulley L', frame L, and pressure-belt V, in the manner and for the purpose herein set forth.

ELIAS H. WILLIAMS,
D. R. W. WILLIAMS.
